UNITED STATES PATENT OFFICE.

CHARLIE A. POST, OF KANSAS CITY, MISSOURI.

KITCHEN-CABINET.

SPECIFICATION forming part of Letters Patent No. 669,961, dated March 12, 1901.

Application filed June 11, 1900. Serial No. 19,858. (No model.)

To all whom it may concern:

Be it known that I, CHARLIE A. POST, of Kansas City, Jackson county, Missouri, have invented a new and useful Kitchen-Cabinet, 5 of which the following is a specification.

My invention relates to kitchen-cabinets; and my object is to provide a device of this character of ornamental appearance and of simple, durable, compact, and cheap construction.

With this and other objects in view the invention consists in certain novel and peculiar features of construction and combinations of parts, as hereinafter described and claimed, 15 and in order that it may be fully understood reference is to be had to the accompanying drawings, in which—

Figure 1 is a front view of a kitchen-cabinet embodying my invention. Fig. 2 is a 20 vertical section of the same, taken through the center of the lower portion and through the upper portion some distance forward of the center.

Referring now to the drawings in detail, 1 25 designates the base or lower portion of the cabinet, the same being preferably of rectangular form, as shown, and provided with a door 2 at its front side and with a cylindrical opening 3 in its top, in which the lower end 30 of the upper or cylindrical bin portion 4 of the cabinet is secured. The upper portion 4 of the cabinet is provided with a conical top or cover 5 and with handles 6 for convenience in moving it from place to place.

35 7 is a vertical partition arranged, by preference, forward of the center of the upper or bin portion and extending from the top of the latter about three-quarters of its length, having its lower edge tapering downward at opposite sides and terminating in a central depending stem 7^a, which terminates a slight distance above the lower portion 1 of the cabinet. (See Fig. 2.)

40 8 designates a pair of vertical partitions extending the full length of partition 7 and its stem 7^a and dividing the space between said partition and the front wall of the upper portion into the chambers 9 and the chamber 10 between chambers 9. The bottom 11 of 45 each chamber 9 coincides with the beveled

lower end of partition 7, and therefore slopes downward and inward from the wall of portion 4 of the cabinet to the partitions 8.

The bottom 12 of chamber 10 is horizontal and provides a support for a removable cup 55 13, the latter being arranged below the downward-converging flanges 14 of chamber 10, said flanges forming practically a continuation of the sloping bottoms 11 of chambers 9 in order to reliably conduct meal or any other 60 product passing from chambers 9 through the openings 15 in said partitions 8 into said cup, said openings being controlled by pivoted valves or slide-plates 16, mounted on partitions 8 within chamber 10. The idea, of course, 65 is to provide a receptacle or cup common to chambers 9, and which while it may receive the contents of both at the same time is adapted to receive from only one, for the reason that they will probably contain different products—for instance, one may contain 70 cornmeal and the other rice.

The top 17 of the chambers 9 has the usual filling-openings, closed by screw-caps 18, access to which is had by removing cover 5. Access to cup 13 in the lower part of chamber 10 is had by opening the hinged door 19, the latter extending from the bottom of said chamber to about the top of the slide-plates 80 or valves 16 in order that said valves or slide-plates may be easily discernible when the door is open.

Arranged above the cup in a vertical series are the spice-cans 20, of the usual or any preferred construction, said spice-cans projecting through holes in the front wall of the cabinet and resting upon supporting-strips 21, extending from the front wall to partition 7.

The lower end of the upper or bin portion of the cabinet is provided with an inverted 90 flange of frustum shape, the same comprising the upper portion 22, the lower portion 24, and the inwardly-projecting flange 23 between said upper and lower portions, said flange serving as the rim for the sieve 25 and 95 as a convenient means of attachment for the diametric sieve-bracing bar 26 at the under side of the sieve.

The agitator resting upon the upper side of the sieve is constructed as follows:

27 is a disk provided with a square hole 28 at its center and with a series of small holes 29 near its periphery.

30 designates a series of skeleton arms of 5 segmental form, said arms being of wire, which preferably can be bent to accommodate any sagging of the sieve, so as to always be in contact with the latter, and terminating in upwardly-projecting lugs 31, engaging contiguous holes 29 of the disk, the outer portion 10 of the arms by preference resting upon the supporting-flange 23 of the bin-flange.

32 is a square bolt extending down through the square hole 28 of the agitator and loosely 15 through holes in the center of the sieve and the brace-bar and also through the arm 34, underlying the brace-bar, and secured reliably in position by a wing-nut 38, engaging the lower threaded end 33 of the bolt. The outer 20 end of arm 34 is bent to substantially V form, as at 36, so that its upper or inner arm shall almost scrape the inner side of flange 24 and its lower or outer arm underlie said flange, a rod or handle 37 being pivoted to the outer 25 end of said arm and adapted to be alternately pushed and pulled to effect the rotation or partial rotation, as desired, of the agitator upon the sieve. The operation of the sieve of course effects the discharge of the flour in 30 a sifted state from the bin 4 down into the pan or receptacle 39 in the lower or base portion of the cabinet.

Secured to the outer side of the bin at opposite sides of the series of cans 20 are rectangular pockets 40, wherein bottles of extracts may be conveniently kept. At opposite sides of the door 19 are secured brackets 35 provided with arms 42, secured to the cabinet, cylindrical cups 44 being supported by 40 having hooks 45 engaged with the said brackets, and underlying the cups are brackets 46, so as to provide a thoroughly rigid and substantial support for the coffee and tea canisters 47, fitting in said cups.

From the above description it will be apparent that I have produced a kitchen-cabinet 45 possessing the features of advantage enumerated as desirable in the statement of invention, and it will also be understood that slight changes may be made as regards the 50 form, proportion, detail construction, and arrangement of the parts without departing from the spirit and scope of the invention.

Having thus described the invention, what I claim as new, and desire to secure by Letters 55 Patent, is—

A kitchen-cabinet, consisting of an upright vertical cylinder, a transverse partition 7, dividing the upper portion of the cylinder into a front chamber and a rear chamber, 60 vertical partitions 8, dividing the front chamber into side compartments 9, 9, and a middle compartment 10, a bottom for compartment 10, downwardly-converging bottoms for compartments 9; said bottoms incidentally 65 forming the bottom of the front chamber, and the top of the underlying or front portion of the rear chamber, a door-controlled opening to give access to the contents of the rear chamber at the lower end thereof, a door-controlled opening to give access to the said middle compartment, valve-controlled openings in partitions 8 to permit the contents of compartments 9 to pass into compartment 10, a top 17 forming the upper end of compartments 9 and 10, caps closing openings in said top, communicating with said compartments 9, and a circular cover for the cabinet which covers the top of the front chamber as well as the open upper end of the rear chamber, 70 substantially as described.

In testimony whereof I affix my signature in the presence of two witnesses.

CHARLIE A. POST.
